UNITED STATES PATENT OFFICE.

RUSSEL G. WOODWARD, OF WAUKEGAN, ILLINOIS, ASSIGNOR TO UNION SPECIAL
MACHINE COMPANY, OF CHICAGO, ILLINOIS, A CORPORATION OF ILLINOIS.

THREAD-CONTROLLING MECHANISM FOR SEWING-MACHINES.

1,135,343.

Specification of Letters Patent. Patented Apr. 13, 1915.

Application filed October 27, 1906. Serial No. 340,896.

To all whom it may concern:

Be it known that I, RUSSEL G. WOODWARD, a citizen of the United States, residing at Waukegan, in the county of Lake, State of Illinois, have invented certain new and useful Improvements in Thread-Controlling Mechanism for Sewing-Machines, of which the following is a description, reference being had to the accompanying drawing and 10 to the letters and figures of reference marked thereon.

My invention relates to take-up mechanisms for sewing machines, and while as to some of its features it may be used for various purposes, said improvements are more particularly adapted to operate in connection with a looper of a chain stitch machine.

An object of my invention is to provide a take-up mechanism for a thread-carrying implement, which keeps the thread under constant control during all the movements of said thread-carrying implement.

A further object of my invention is to provide a take-up mechanism which includes means whereby upon the accidental backward turning of the machine the thread is disengaged from the take-up, and all danger of winding the thread into the take-up is therefore avoided.

These and other objects will in part be obvious, and in part be hereinafter more fully described.

My invention consists in the novel parts and improvements hereinafter shown and 35 described.

In the accompanying drawings, which form a part of this specification: Figure 1 is a front elevation of a sewing machine provided with my improvements, the front of 40 the casing and the work plate being removed to more clearly show the operating mechanism; Fig. 2 is a front view of the base portion of the machine shown in Fig. 1 on an enlarged scale, certain of the parts being 45 broken away and omitted to more clearly show the invention; Fig. 3 is a front view of my thread-controlling cam, also showing the thread guide and its relation thereto; Fig. 4 is a view similar to Fig. 3 of the thread-

controlling cam in a different position; Fig. 50 5 is a view similar to Fig. 3 of the thread-controlling cam in another position; and Fig. 6 shows a modification in the form of my thread-controlling cam.

In the drawings, the bed plate 6 has rising 55 therefrom an overhanging arm 20, which carries at its forward end the usual needle head 21. Reciprocating in said needle head 21 is a needle bar 22, carrying a needle 23. The needle bar receives its reciprocation 60 from a needle lever 24, which is pivoted at 25 to the overhanging arm, and is connected by a link 26 to said needle bar. This needle lever is oscillated about its pivot by a link 27, which is pivoted to said needle lever at 65 one end, and is operatively connected at its other end to an eccentric 28, on the main shaft 10. Rigidly secured to the needle lever is a thread-controlling arm 29, which co-operates with the tension 30 and thread 70 guide 31, in controlling the needle thread.

The needle lever 24 is provided with an extension 31, which is connected by means of a link 7 to the looper carrier 2. The looper 1 is mounted in the usual manner in the 75 looper carrier 2, which in turn is pivotally connected to a looper support 3, mounted on a shaft 4, carried by the brackets 5, 5, rising from the bed plate 6.

The looper receives its lateral or needle- 80 avoiding movement through the arm 8, which is fixed to the looper support 3, and at its upper end is pivoted to an eccentric strap 9, which co-operates with an eccentric carried by the main shaft 10.

It will be noted that as the needle lever is oscillated the looper carrier is also oscillated in timing therewith through the link 7. The link 7 is pivoted to the looper carrier at a point 32. This point 32 is a shorter distance from the pivotal point of the looper carrier, so that while the point of connection between the link 7 and the carrier moves in timing with the point of connection between the link 7 and the needle lever extension, the looper moves considerably faster. The thread for the looper is led through a tension 33 carried by the head of the ma- 95

chine, thence through a thread guide 34 at the lower end of the needle lever extension and from the thread guide 34 said thread passes through my improved take-up mechanism to the looper 1.

Inasmuch as the looper moves at a greater speed than the thread guide 34, it is necessary to provide some means for taking care of the slack produced in the looper thread by this difference in the timing of these parts, and also to care for the usual slack formed and to draw off sufficient thread from the supply for the forming of the stitches. For this purpose I have provided my improved take-up mechanism, which as shown in the present embodiment of my invention comprises a thread-controlling cam 19, mounted on the main shaft 10, intermediate the thread guide 34 and the looper. Coöperating with said thread-controlling cam 19 is a thread-retaining device 17, which operates to properly position the looper thread relative to the thread-controlling cam. Said thread-retaining device 17, as shown in the drawing, is formed from a single wire 14, carried by a plate 13, which is adjustably secured to the bed plate 6, by means of a slot 11 and a screw 12. Said thread-retaining wire 14 extends upwardly and backwardly, as shown at 18 to a position inside of the smallest radius of said thread-controlling cam. The thread-retaining wire is then bent downwardly and outwardly, as at 17, to a position outside of the largest radius of said thread-controlling cam. The ends of the thread wire 14, which extend up on each side of the thread-controlling cam, are preferably joined as at 15.

It will be obvious from the above description, that I have provided a thread-guiding or retaining device which operates to hold the thread at each side of the thread-controlling cam. Furthermore, inasmuch as the thread retainer extends to a position inside of the smallest radius of the thread-controlling cam, said thread-controlling cam will be constantly in engagement with the looper thread and consequently said looper thread will be under control continually during all the movements of the looper.

With the thread-retaining device shaped as shown in the drawings, my thread-controlling mechanism may be easily threaded, as all that is necessary is to slip the thread running over the thread guide 34 to the looper, underneath the forwardly projecting portion 17 of the thread-retaining wire. The thread-controlling cam turning in the direction indicated by the arrow in Figs. 3, 4 and 5, carries the thread into the thread slot formed by the thread wire, and the continued movement of the thread cam holds the thread within said thread-guiding member.

If for any reason the machine is accidentally turned in the wrong direction, the thread-controlling cam immediately forces the thread down the thread slot and out of said thread-guiding member, and, therefore, all liability of the thread being wound up by the thread cam on the backward turning of said cam is avoided. Furthermore, when a single thread cam is used, instead of the double cams as heretofore, with the thread-retaining wire on each side of the said cam, the liability of winding the thread into the thread cam upon the breaking of the thread or the turning of the machine in the wrong direction, is also avoided. The purpose of adjusting the supporting plate 13 which carries the thread-guiding members, is to properly locate said thread-guiding members on each side of the thread-controlling cam.

The operation of my thread-controlling cam is as follows: Starting with the needle at its highest point, which would place the looper in its most forward position, the thread-controlling cam is in the position shown in Fig. 3, and the looper thread is carrier substantially straight across from the guide on one side of the thread-controlling member to the guide on the other side of said member. At this time the looper thread also extends from the previous stitch through the needle loop on the looper to the eye of the looper at the point which is at considerable distance to the left of the needle, and then back through the eye at the heel of the looper. When the looper starts to return, the thread eye 34 on the needle lever extension moves to the right, as viewed in Fig. 1, but at a rate of travel slower than the looper, thus causing slack in the looper thread. The looper also is withdrawing from the needle loop at this time, and is giving up the thread drawn by the movement of the looper eye beyond the line of seam or the needle. The thread-controlling cam moves from the position shown in Fig. 3 to that shown in Fig. 4, and this slack in the thread is taken up, drawing the looper thread back through the eye of the looper, so as to properly position the thread for the entrance of the needle into the looper loop, and at the same time when the looper thread is under strain thread is drawn by the thread-controlling cam, and thread guide 34 from the supply through the tension 33. This operation of taking up slack continues until the needle gets well into the loop of thread formed by the looper, and the thread-controlling cam has passed slightly the position shown in Fig. 4, when the thread slips off the enlargement A or is cast off. The needle loop is now cast off from the looper, and is being drawn up closely to the under side of the material.

and the looper thread is slack, so as not to interfere with the drawing up of this needle loop.

When the looper is at its extreme backward position, the eye of the looper is at some distance from the needle and the previous stitch and the thread extends from the work at the stitching point through the looper eyes, and the take-up to the thread 5 guide on the needle lever extension. As the looper moves forward to enter the needle loop, the thread guide 34 moves forward and slack is caused in the looper thread. The enlargement C, Fig. 5, is now coming 10 into engagement with the thread between the thread guides and the slack is taken up, said enlargement pulling the slack formed in front of the looper as it moves toward the needle through the looper eyes. After 15 the looper enters the needle loop the enlargement C passes the thread and slack is gradually given up to the movements of the looper; said looper moving beyond the needle and forming the looper thread loop 20 requiring thread at this time. The feed of the fabric commences as the looper is reaching the forward end of the stroke, and the thread cam is approaching the position shown in Fig. 3, so that thread is easily 25 drawn from the supply for the feeding of the material as the thread is at this time substantially straight from one thread guide to the other. The feed commences, however, while slack is still retained by the 30 thread cam, so that the drawing of the thread from the supply is slow at first, followed by a rapid pulling from the supply as the slack is exhausted. It will be noted, therefore, that my improved thread cam 35 operates, starting with the position shown in Fig. 3, to first take-up slack quickly, then allow slack to be given up quickly, take up slack quickly a second time, and to slowly allow feed of thread from the supply, and 40 finally the rapid feeding ahead of the thread by the movement of the material.

In my modified form of take-up shown in Fig. 6, I have provided my thread-controlling cam with a second enlargement 45 slightly in the rear of the enlarged portion of the thread cam shown in Figs. 3, 4 and 5. In the operation of my machine, this form of thread cam operates practically in the same manner as the thread-controlling cam shown in the other figures, except that after the thread has been cast off by the thread-controlling cam, when the enlargement A passes the thread guides, the thread 50 is again slightly taken up by the enlargement B to straighten out the thread between the loop pulled up to the throat plate and the front eye of the looper. This thread-controlling cam operates to keep the looper thread constantly under control in the same

manner as the thread-controlling cam shown 55 in the other figures. Said cam will also operate to hold the thread within the thread guide and to cast the thread from the thread guide upon the accidental backward turning of the machine.

It will be noted that the thread guides are located in advance of the center of the take-up, and have an open mouth extending toward the front of the machine, whereby the same is easy of access for the purpose of 70 threading.

While I have shown my thread guides as formed from a wire secured to the base plate and extending up into proper relation to the thread-controlling cam, it will be obvious 80 that said thread guides may be formed from sheet metal or in any other way, as long as the relative position of said guides to the thread-controlling cam is maintained.

It will be obvious that many minor 85 changes in the details of the construction herein shown may be made without departing from the spirit of my invention. It will also be obvious that said take-up mechanism may be applied to the needle thread, or used 90 in any other relation in a machine of the character herein disclosed, for the purpose of controlling the thread leading to a thread-carrying implement.

Having thus described my invention, what 95 I claim as new and desire to secure by Letters Patent, is:—

1. A looper, means for operating the same, and a rotary take-up for the looper thread, including a thread-controlling element, means for operating said element, and means to retain the thread against the face of the thread-controlling element, said thread-controlling element having means to successively take up the looper thread and 100 give slack thread on the forward movement of the looper, and to take up thread and again give up slack thread to the looper on its backward movement.

2. A looper, means for operating the 110 same, and a rotary take-up for the looper thread including a rotating thread-controlling element, means for operating the same, and means for retaining the thread against the face of said thread-controlling element, 115 said thread-controlling element being shaped so as to take up the thread, give slack to the thread on the forward movement of the looper, and control the slack as it is given to the looper, and to take up thread and 120 again give slack thread to the looper on its backward movement, and control the slack given to the looper in its backward movement.

3. A rotary take-up including in combination, a thread-controlling member, means for rotating said member, and means to retain the thread against the operative face of

said thread-controlling member, said retaining means having its thread-engaging surface extending from a point within to a point without the largest radius of said 5 thread-controlling member; substantially as described.

4. A rotary take-up including in combination, a thread-controlling member and means to retain the thread against the operative 10 face of said thread-controlling member, said retaining means having an open mouth extending beyond the maximum diameter of the thread-controlling member for convenience in threading.

15 5. A rotary take-up including in combination, a thread-controlling member, and means to retain the thread against the operative face of said thread-controlling member, said retaining means having an open mouth extending beyond the maximum diameter of the thread-controlling member for convenience in threading and a support for said retaining means located in advance of the center of the thread-controlling member; 20 substantially as described.

30 6. A rotary take-up including in combination, a thread-controlling member, means to operate said thread-controlling member, and means to retain the thread in operative position relative to said thread-controlling member, and also to deflect the thread out of the path of the thread-controlling member when the same is accidentally turned in the wrong direction whereby the thread is prevented 35 from being wound up in the thread-controlling member; substantially as described.

40 7. A rotary take-up including in combination, a thread-controlling member, means for rotating the same, a thread-retaining device holding the thread at all times in operative position against the thread-controlling member, said thread retaining device having a thread guiding slot extending from a point 45 inside of the minimum diameter of the thread controlling member to a point outside the maximum diameter thereof, whereby the rotation of the thread-controlling element tends to continuously hold the thread at the 50 inner end of said thread-guiding slot; substantially as described.

55 8. A rotary take-up including in combination, a thread-controlling member, means for rotating said member, a vertically arranged thread-retaining wire extending on each side of said take-up member and bent backward to form thread guides, the ends of said 60 thread wires being joined in front of the thread-controlling member; substantially as described.

60 9. A rotary take-up including in combination, a thread-controlling device, means for rotating said device, means to guide the

thread across the operative face of said thread-controlling device, said thread-guiding means having open ended slots between which the thread-controlling device projects, said slots extending from a point inside of the minimum diameter of the thread controlling device, to a point outside the maximum diameter, the rotation of said thread-controlling device maintaining the thread at the top of said thread-guiding slots; substantially as described. 65 70

10. In a sewing machine, the combination 75 with a looper, means for operating said looper, a thread guide through which the looper thread is led to the looper, said thread guide being movable forward and backward in timed relation to the looper and at a speed differing therefrom, a rotary take up cam engaging the looper thread between said thread guide and looper for controlling the slack of the looper thread, and thread guides located at opposite sides of said cam 80 for engaging the looper thread and holding said thread in contact with said cam. 85

11. In a sewing machine, the combination 90 with a looper and means for operating the same, of a thread-controlling device and means for operating said device, whereby the said device operates to take up the slack thread caused by the receding movement of the looper and to pull thread from the supply; substantially as described. 95

12. In a sewing machine, the combination 100 with a looper and means for operating the same, of a rotary take-up acting upon the looper thread and operating to take up, pull off and allow the looper to feed the thread while the same is moving forward; substantially as described.

13. A thread-controlling mechanism including in combination, thread guides, means for supporting said thread guides in adjusted positions, a thread-controlling cam arranged to operate between said thread guides, and means for rotating said cam the adjustment of said guides being at substantially right angles to the plane of the thread controlling cam; substantially as described. 110

14. A thread-controlling mechanism including in combination, an adjustable plate, a thread-guiding wire secured thereto and bent to form thread guides, a thread-controlling cam arranged to operate between said thread guides, and means for rotating said cam; substantially as described. 115

15. A thread-controlling mechanism including in combination, a thread-guiding wire, fixed to the frame of the machine, said wire being bent to form a U-shaped member, then extending upwardly and bent back upon itself to form thread guides, a thread-controlling cam arranged within the said U-shaped member and engaging a thread pass- 120 125

ing through said thread guides, and means for operating said cam; substantially as described.

16. A thread-controlling mechanism including in combination, an adjustable plate, means for holding the same in its adjusted position, a thread-guiding wire fixed to said plate and extending upwardly and backwardly and then bent upon itself to form 10 thread guides, a thread-controlling cam co-

operating with said thread guides, and means for operating said cam; substantially as described.

In testimony whereof I affix my signature, in presence of two witnesses.

RUSSEL G. WOODWARD.
